[57] CLAIM

The ornamental design for an emblem, as shown and described.

DESCRIPTION

FIG. 1 is a face view of an emblem showing my new design;

FIG. 2 is a face view of an emblem showing a modified form of my new design;

FIG. 3 is a face view of an emblem showing another modified form of my new design; and

FIG. 4 is an edge view of the emblem shown in FIG. 1. The rear of each embodiment is unornamented, and each embodiment is of the same uniform thickness shown in FIG. 4.

FIG.4

FIG. I

FIG. 2

FIG. 3
